COIN COLLECTING DRAWER ALARM SWITCH
John H. Fasal, New York, N.Y., and Eli Levy, Bloomfield, N.J., assignors to Specialties Development Corporation, Belleville, N.J., a corporation of New Jersey
Filed Sept. 18, 1963, Ser. No. 309,727
11 Claims. (Cl. 200—61.61)

The present invention relates to alarms, and more particularly to an alarm for detecting tampering with a coin collecting drawer.

In many instances coin operated machines are installed in locations where they cannot be watched to prevent theft of the coins collected by the machines. For example, coin operated washing and drying machines for use of the tenants of an apartment building are usually installed in an open room or space in the basement of the building and receipts of the machines are collected infrequently. Consequently, the receipts are exposed to theft at such hours when the machines are not in use. In addition to the loss of money, the coin collecting arrangement of the machines is damaged in perpetrating the theft and requires immediate repair to prevent subsequent users of the machines from recovering the coins they deposited to operate the machines.

A conventional coin collecting arrangement for coin operated machines generally comprises a casing mounted within the housing of the machine and having a bottom, a rear wall, side walls and a front opening accessible from the exterior of the housing; a coin collecting drawer in the casing having a bottom, a rear wall, side walls, and a front wall overlying the front opening; and means operable from the exterior of the front wall for releasably locking the drawer in the casing.

Such an arrangement can be broken into by inserting a tool between the drawer front wall and the surface it overlies, and prying the front wall outwardly to bend the same outwardly of the drawer whereby the coins in the drawer are accessible for removal.

Accordingly, an object of the present invention is to provide an alarm for immediately detecting the foregoing manner of tampering with a coin collecting drawer.

Another object is to provide such an alarm which also detects unauthorized unlocking and withdrawal of the drawer.

Another object is to provide such an alarm which is not visible from the exterior of the machine.

Another object is to provide such an alarm which cannot be defeated by shutting off the electrical power in the area where the machine is located.

Another object is to provide such an alarm which can be installed conveniently on newly fabricated machines as well as machines already in use.

Another object is to provide such an alarm which is simple and economical in construction and reliable in operation.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description, and is shown in the accompanying drawing, forming a part of the specification, wherein:

FIG. 1 is a plan view, partly in section, of an alarm in accordance with the present invention.

FIG. 2 is a sectional view taken along the line 2—2 on FIG. 1.

FIG. 3 is a sectional view taken along the line 3—3 on FIG. 1 illustrating a switch assembly in elevation.

2

FIG. 4 is a simplified wiring diagram of an alarm network controlled by the alarm.

Referring now to the drawing in detail, there is shown an alarm for a coin collecting drawer which generally comprises a casing 10 mounted within the housing H of the machine and irremovably secured thereto, a coin collecting drawer 11 in the casing, locking means 12 for releasably locking the drawer in the casing, and a switch assembly 14 between adjacent sides of the casing and the drawing for operating an alarm network 15 (FIG. 4) in response to tampering with the drawer.

The casing 10 has a bottom 16, a rear wall 17, side walls 18 and 19; and a front wall or frame 20 formed with an opening 21 for receiving the drawer.

The drawer 11 has a bottom 22, a rear wall 24, side walls 25 and 26, and a front wall 27 overlying the opening 21 and the front wall or frame 20 to provide a closure for the drawer and the casing.

The locking means 14 is of conventional type and includes a key operated lock element 28 mounted on the drawer front wall 27 for inserting a key from the exterior of the housing H, a lock element 29 adapted to be releasably locked with the element 28, and a rod 30 having one end secured to the lock element 29 and having its other end secured to the casing rear wall 17 and extending through an opening 31 in the drawer rear wall 24.

The switch assembly 14 generally comprises an electrical switch 32 having switch contacts and an element 34 having an end for engaging and biasing one of the switch contacts in one switching position and having another end engaging the inner side of the drawer front wall 27 to maintain switch contact bias when the drawer is locked in the casing, whereby, upon movement of the drawer front wall away from the casing opening 21, the element 34 relieves the switch contact bias to allow the switch contact engaged by the element 34 to assume another switching position.

In the illustrative embodiment herein, the switch assembly 14 includes a plate 35 having the switch 32 mounted on transverse wall 36 at the rear end thereof formed with an aperture 37 for slidably supporting the element or rod 34, and the switch 32 includes a fixed rear contact 38 and a resilient front contact 39 engaged by the rear end of the rod 34 to bias the contact 39 into engagement with the contact 38 when the front end of the rod 34 is in engagement with the drawer front wall 27 as shown in FIG. 1, whereby, upon movement of the drawer front wall away from the casing opening, the rod 34 is displaced and the contacts 38 and 39 disengage (FIG. 3).

Preferably, a switch assembly 14 is positioned between the casing and drawer side walls 18 and 25 and 19 and 26, respectively, so that tampering at either side of the drawer front wall effects a switching operation for controlling alarm network 15.

The switch assembly is held in place by positioning the front edge thereof against the back of the frame 20 and the lower edge thereof on the casing bottom 16 (FIGS. 1 and 2) and threading upper and lower screws 40 and 41 into the wall 36 which can be adjusted to position the rear ends thereof for engagement with the casing rear wall 17 so that the switch 32 is spaced from the rear wall 17.

If the casing is constructed of magnetic material which is usually so, the switch assembly plate 35 is attached to the adjacent casing side wall by a magnet 42 carried by the plate.

As shown in FIGS. 2 and 3, the magnet 42 may be positioned beneath the rod 34 at its front end. The rod 34 may be formed of magnetic material so that, when it is released due to tampering, it falls on the magnet and is held in its displaced position by the magnet.

In FIG. 4, a wiring diagram of the alarm network 15 is shown which includes the switches 32 of two switch assemblies 14, a relay coil 44 and a source of electrical energy 45 connected in series; a switch 46 having a contact 47 and an arm 48 operated by the coil 44 to hold it out of engagement with the contact 47 when the coil is energized; and a bell 49 connected in series with the switch 46 and the source of energy 45.

When the drawer is locked in its closed position as shown, both switches 32 are closed and the relay coil 44 is energized to hold the switch arm 48 out of engagement with the contact 47, whereby the bell 49 is de-energized. Upon opening of either or both switches 32 the switch arm 48 drops out or is urged by a spring 50 to engage the contact 47 and effect energization of the bell to give an alarm.

From the foregoing description, it will be seen that the present invention provides a simple, practical and reliable alarm for detecting tampering with coin collecting drawers or the like.

As various changes may be made in the form, construction and arrangement of the parts herein, without departing from the spirit and scope of the invention and without sacrificing any of its advantages, it is to be understood that all matter herein is to be interpreted as illustrative and not in any limiting sense.

We claim:

1. In a coin collecting drawer alarm, the combination of a casing having a bottom, a rear wall, side walls, and a front opening; a coin collecting drawer in said casing having a bottom, a rear wall, side walls spaced from said casing side walls, and a front wall overlying said front opening; means operable by a key from the exterior of said front wall for releasably locking said drawer in said casing, said drawer being normally locked in closed position; and a switch assembly between at least one of said casing side walls and said drawer side wall adjacent thereto, and said switch assembly including an electrical switch having switch contacts and an element having an end for engaging and biasing one of said switch contacts in one switching position and having another end engaging the inner side of said front wall to maintain switch contact bias when said drawer is locked in said casing, whereby, upon slight movement of said front wall away from said casing front opening while said drawer remains locked in closed position, said element relieves the switch contact bias to allow said switch contact engaged by said element to assume another switching position.

2. In an alarm according to claim 1, wherein said switch contact engaged by said element is resilient.

3. In an alarm according to claim 1, wherein said element is a rod.

4. In an alarm according to claim 3, wherein said switch assembly has means for slidably supporting said rod.

5. In an alarm according to claim 3, wherein said switch contacts are adjacent the rear wall of said casing.

6. In an alarm according to claim 5, wherein said switch

assembly includes means for spacing said switch contacts from the rear wall of said casing.

7. In an alarm according to claim 6, wherein said spacing means is adjustable.

8. In an alarm according to claim 1, wherein said casing is constructed of magnetic material and said switch assembly carries a magnet attaching said assembly to said casing side wall.

9. In a coin collecting drawer alarm, the combination of a casing having a bottom, a rear wall, side walls, and a front wall formed with an opening; a coin collecting drawer in said casing having a bottom, a rear wall, side walls spaced from said casing side walls, and a front wall overlying said front wall and its opening; means operable by a key from the exterior of said front wall for releasably locking said drawer in said casing, said drawer being normally locked in closed position; and a switch assembly between at least one of said casing side walls and said drawer side wall adjacent thereto, said switch assembly including a plate extending from said casing front wall towards said casing rear wall, a fixed rear switch contact and a resilient movable front switch contact adjacent said rear contact both mounted on said plate at the rear thereof, a rod having its front end in engagement

25 with the inner side of said drawer front wall and having its rear end in engagement with said movable front switch contact to bias the same into engagement with said fixed rear switch contact when said drawer is locked in said casing, means for supporting the rear end of said rod, 30 and means for attaching said plate to said casing side wall, whereby, upon slight movement of said drawer front wall away from said casing front wall, said rod follows said drawer front wall while said drawer remains locked in closed position and allows said movable switch contact 35 to move out of engagement with said fixed switch contact.

10. In an alarm according to claim 9, wherein said plate has adjustable means at its rear end for engaging said casing rear wall to space said switch contacts therefrom and to cause the front of said plate to engage said casing front wall.

11. In an alarm according to claim 9, wherein said attaching means is a magnet, said casing is formed of magnetic material to attract said magnet, and said rod is positioned above said magnet and is formed of magnetic material, whereby when said drawer front wall disengages the front end of said rod said rod is attracted by said magnet and is held in a position to allow said switch contacts to remain out of engagement.
